(57) **CLAIM**

The ornamental design for an electric brake drum, as shown and described.

DESCRIPTION

FIG. 1 is a top perspective view of an electric brake drum in accordance with my design;

FIG. 2 is a bottom perspective view thereof;

FIG. 3 is a top view thereof;

FIG. 4 is a bottom view thereof;

FIG. 5 is a front view thereof;

FIG. 6 is a rear view thereof;

FIG. 7 is a left side view thereof;

FIG. 8 is a right side view thereof; and,

FIG. 9 is a cross-section taken along line 9-9 of FIG. 3.

The broken lines show portions of the electric brake drum that form no part of the claimed design.
